UNITED STATES PATENT OFFICE.

HENRY F. SNAMISKA, OF BREMERTON, WASHINGTON.

PRECIOUS-METALS CONCENTRATOR.

Application filed January 24, 1923. Serial No. 614,824.

To all whom it may concern:

Be it known that I, HENRY F. SNAMISKA, a citizen of the United States, residing at Bremerton, in the county of Kitsap and 5 State of Washington, have invented certain new and useful Improvements in Precious-Metals Concentrators; and I do hereby declare the following to be a full, clear, and exact description of the invention, such as 10 will enable others skilled in the art to which it appertains to make and use the same.

This invention relates to improvements in concentrators for ores and more particularly to concentrators for ores containing 15 precious metals and the like.

An object of the invention is to provide a suitable concentrator for ores containing precious metals which will be so constructed as to efficiently separate and concentrate the 20 precious metals from the mass of earth and gravel usually collected with said metals when they are mined.

Another object of the invention is to provide a suitable ore concentrator for precious 25 metals which will be provided with a receiving chamber and a plurality of pivoted flumes and means for concentrating and collecting the precious metals from the waste earth and gravel which accompanies said 30 metals when mined.

A further object of the invention is to provide a suitable ore concentrator which will be highly efficient in operation and quite inexpensive to manufacture. Other objects 35 will appear as the description proceeds.

In the accompanying drawings which form a part of this application, Figure 1 is a front elevation of my improved ore concentrator.

40 Fig. 2, is an end elevation of the same.

Fig. 3, is a sectional view taken on a line 1-1 of Figure 1.

Fig. 4, is a detail view showing the riffle plates in lowered position and

45 Fig. 5 is a detail view showing the riffle plates in elevated position.

Like characters of reference are used throughout the following specification and the accompanying drawings to designate 50 corresponding parts.

A suitable frame is provided with a base portion 1, and a plurality of vertically extending supporting members 2 which are connected adjacent their upper ends by the horizontally disposed member 3. A receiving 55 hopper 4 is positioned centrally of the

frame and adjacent its upper portion and has connected therewith a chute 5, with a flared skirt 6 at its lower end. Positioned directly under the skirt portion 6 is an inclined screen or sieve 7, which is supported by the braces 8. Adjacent the lower extremity of the screen 7 is a laterally extending chute 9 which is adapted to carry off the larger stones and matter that will 60 not pass through the screen 7. Positioned below the screen 7 is a divided separating platform 10, which is downwardly inclined from its central portion to its outer extremities and serves to direct the mass of earth, 70 gravel and precious metals to the oppositely disposed chutes or flumes 11. These flumes 11 are supported on cross members 12 and are further held in position at their inner ends by means of the chains 13. The outer 75 vertically extending supporting members 2, carry a plurality of spaced brackets 14 which support the transversely extending supporting bars 15, to which are attached the chains 16, so that the same will not be 80 misplaced or lost. The lower end of the flumes 11 are adapted to engage a seat on the bars 15, and normally to extend in a downwardly sloping direction. A plurality of riffles 17 are carried by the levers 18 and 85 are pivoted at 19 to the said walls of the said flumes 11 and normally rest on the bottom of said flumes. A connecting rod 20 is connected to the upper ends of the arms 18, and is attached at its outer end to a pivoted 90 lever 21 which is operable in a suitable quadrant 22, so that by drawing the lever 21 in one direction all of the riffles will be elevated, while pushing the lever 21 in the opposite direction will lower the said riffles. A suitable transversely extending baffle plate or door 23 is 95 mounted transversely of each of the flumes 11, and is held in position by means of the upwardly and inwardly turned hooks 24. A suitable weight 25 is carried by the door 100 23 and normally tends to hold the same in lowered position.

Cables 26 are attached at the outer ends of the flumes 11, and extend upwardly over the pulleys 27 and 28, and downwardly to a 105 suitable reel or winding device 29, so that the flumes may be raised or lowered as desired.

A foot board 30 is positioned at one side of the frame so that ready access may be had 110 to the flumes when desired. A downwardly and outwardly turned collecting chute 31 is

positioned underneath the inner ends of the flumes 11, and is provided at its lower ends with a door 32 which is operable by a screw 33. A laterally extending pipe 34 is positioned adjacent the top of the chute 31, so that when too much water is allowed to enter the said chute, it will overflow through the said pipe.

In operation the ore is discharged from the inlet 5 through the screen 7 and on the dividing platform 10, where it will be forced into the flumes 11 by means of a heavy stream of water passing through the pipe 35. The water will cause the lighter portions of the ore, viz, the gravel and dirt to be washed down over the riffles and out the ends of the flumes while the precious metal and a very small quantity of the waste material is collected adjacent the said riffles. The flumes are then elevated by means of the cables 26 so that their inner ends are in the lowermost position and a supply of water is discharged from the outer ends at the same time as the riffles are elevated, which action will wash the material and metals collected into the chute 31, where they will be discharged through the door in its lower end to suitable conveyances which will transport the same to the nearest retort where the precious metal is separated by being subjected to a very high temperature of heat which will melt the same so that it may be drawn off from the bottom of the smelting retort. Thus it will be seen that instead of transporting a large quantity of waste material with a small quantity of precious metals to the retort, it will now be necessary to transport only a very small percentage of waste material with the metals. This will mean a great saving in expense, as so much waste material heretofore was needlessly transported a great distance as the smelting retorts are very far remote from the mines.

Many minor changes in detail of construction may be resorted to without departure from the spirit of the invention.

Having thus described my invention, what I claim as new and desire to secure by Letters Patent of the United States is:

1. An ore concentrator comprising a frame, a centrally disposed receiving chute, a sloping sieve disposed under said chute, a dividing platform under said sieve, a vertical conduit beneath the platform, spaced pivoted flumes at either side of said platform adapted to be rocked to discharge either inwardly into the vertical conduit or outwardly, riffles in said flumes and means for rocking said flumes. 55

2. An ore concentrator comprising a frame, a centrally disposed receiving chute, a sloping sieve disposed under said chute, a dividing platform under said sieve, spaced pivoted flumes at either side of said platform, pivoted riffles in said flumes, means 65 for raising and lowering said riffles and means for raising and lowering said flumes.

3. An ore concentrator comprising a frame, a centrally disposed receiving chute, a sloping sieve disposed under said chute, a dividing platform under said chute, a laterally extending discharge chute adjacent said sieve, a water inlet in said receiving chute, spaced pivoted flumes at either side of said platform, pivoted riffles in said flumes, 75 means for raising and lowering said flumes, a collecting chute positioned beneath the inner ends of said flumes, an overflow therefor, and means for opening and closing the bottom of said collecting chute. 80

4. An ore concentrator comprising a frame, a centrally disposed receiving chute, a sloping sieve disposed under said chute, a dividing platform under said sieve, spaced pivoted flumes at either side of said platform, a plurality of interconnected riffles in said flumes, means for operating the same, a detachable pivoted weighted door or baffle in each of said flumes and means for raising or lowering said flumes. 85

In testimony whereof I affix my signature.

HENRY F. SNAMISKA. 90
